TRAVERSE MECHANISM FOR WINDING MACHINES

Penrose E. Chapman, St. Louis, Mo.

Application February 6, 1939, Serial No. 254,809

12 Claims. (Cl. 74—59)

The invention relates more particularly to the traverse mechanism of a winding machine, and for purposes of disclosure but not of limitation it has been illustrated and will be herein described in connection with the essential parts of a coil winding machine of the type described and claimed in my prior U. S. Patent No. 2,186,820, granted January 9, 1940.

In the machine of the said prior patent the drive for the traverse mechanism is accomplished through a reversing friction gearing comprising a pair of spaced friction discs, constituting the driving elements, and a driven element in the form of a wheel or roller oscillatably mounted between said driving elements for alternative engagement therewith. The power to cause the automatic oscillation of the driven wheel and consequent reversal of the traverse is derived through the said wheel itself, but this is objectionable in some instances, and the primary object of the present invention is to provide means whereby the power necessary to shift the wheel into alternate engagement with the discs to reverse the traverse is secured elsewhere than through the reversing drive.

With the above and other objects in view, which will appear as the description proceeds, the invention consists in the novel details of construction and in the novel combinations and arrangements of parts, more fully hereinafter disclosed and particularly pointed out in the appended claims.

Referring to the accompanying drawing forming a part of this specification, in which like reference characters designate like parts in all the views:

Figure 1 is a perspective view, partly diagrammatic and partly in section, illustrating the essential elements of a coil winding machine of the type disclosed in my said prior patent, including the friction disc and roller reversing drive, with roller shifting mechanism constructed in accordance with the present invention applied thereto;

Fig. 2 is a vertical sectional view through the mechanism constituting the invention, for oscillating the driven friction wheel to secure reversal of the traverse;

Fig. 3 is a vertical sectional view at right angles to Fig. 2, taken approximately on the plane indicated by the line 3—3 of said figure, looking in the direction of the arrows;

Fig. 4 is a top plan view of certain of the parts shown in Fig. 2; and

Fig. 5 is a horizontal sectional view, taken ap-

proximately on the plane indicated by the line 5—5 of Fig. 3, looking down.

The essential elements of the prior machine, which are designated by the same reference characters as in said Patent No. 2,186,820, may be briefly described as comprising an electric or other motor 11 driving a shaft 10, which through suitable change speed gearing (not shown) drives a vertical spindle 19 carrying the spaced driving discs 20 and 21 between which is positioned the driven wheel or roller 25. The said wheel is carried by a shaft 26 journaled in bearings 27 and 55 which are mounted to provide for vertical oscillatory movements of the shaft 15 whereby the wheel 25 may be brought alternatively into engagement with the discs 20 and 21. The shaft 26 is provided with a threaded sleeve or quill 31 which is engaged by the traverse nut 41 of the traverse carriage 40, to which is secured the traverse bar 45. The bar 45 carries a sheave 49 which guides the wire or strand 50 to the coil 51, all as will be clear from Fig. 1.

The bearing 27 is carried by a link 69 (Figs. 2, 3 and 4) which is supported by a pair of spring arms 66 and 66' which arms constitute one element of a bell crank assembly, the other elements of which comprise the rock shaft 65 and arm 11. Adjustable stop nuts 61 and 61' are mounted on a threaded shipper rod 60 and are engageable by 25 a projection on the traverse carriage 40 to produce reversal of the traverse through the mechanism constituting the gist of the present invention and about to be described. The shipper rod 60 also carries a button 62 arranged to coact with 30 a spring pressed trigger 63 in substantially the same manner as in my said prior patent.

A countershaft 90 is suitably journaled in the machine frame, and is driven from any convenient source so long as the power is not taken 40 through the friction drive element 25. For illustrative purposes I have shown it as being derived from the motor 11 through shaft 10, sprocket 12, chain 14 and sprocket 103, although obviously other drives may be employed.

A cam 91 is mounted upon the countershaft 90 in juxtaposition with the lower end of a pivotally mounted cam follower 92. The said lower end of the follower is disposed at an angle to the body thereof, as clearly shown in Figs. 1 and 2, 50 and is apertured to provide the upper and lower cam-engaging faces 93 and 94 respectively, see Fig. 3, which faces are adapted to be alternately aligned with the cam 91 as the follower is swung upon its pivot 95. When the follower is in the full line position shown in Fig. 2 the face 93 will

be in line with the cam and rotation of the latter will raise the follower, whereas when the follower is swung to the broken line position illustrated in said figure, the face 94 will be aligned with the cam and rotation thereof will lower the follower.

Swinging of the follower between the two positions is accomplished automatically by means of the shipper rod 60 through the medium of the spaced pins 102 carried by the extension 60' of said rod, one to either side of the follower, it being understood that the said rod is moved longitudinally at the end of each traverse through engagement of the carriage 40 with the nuts 61 and 61', as in my prior Patent No. 2,186,820.

The pivot 95 of the follower 92 is disposed between the free end portions of a pair of leaf springs 100, the other ends of which are rigidly secured to the rock shaft 65, see Figs. 2 and 4; and by reason of the fact that at the time of the raising or lowering of the follower 92 by the cam 91, the said rock shaft is held against oscillation through the engagement of the lower end of the bell crank arm 71 with one of the grooves in trigger 63, such raising and lowering movements of the follower 92 will, through its pivot 95, place one or the other of the springs 100 under tension.

In order to provide a latch or lock for the springs 100 and thereby prevent loss of their tension as the cam 91 recedes, I may make the ends of the pivot pin 95 of a conical or any other hump like cross-section as is shown in Fig. 2 and arrange that they engage the humps 96 carried by the chimney like housing 97 as they travel up or down. The movable humps on this pin 95 are held in place against the face of the housing and the humps 96 by any suitable means as the pair of U springs 98.

From the above construction it can be seen that as the cam follower 92 is moved either up or down its pivot pin 95 will be compelled to climb over the humps 96 and will be retained on whatever side of the said humps it happens to be by the pressure of the springs 98.

In order that the cam 91 may not be constantly clicking against the cam follower 92 when the follower is at rest I proportion the humps 96 so that by the time the pivot pin 95 has slid all the way down either side of the said humps it will have traveled under the influence of springs 98 a slightly greater distance than the throw of the cam 91.

Feed control, tripping or reversing action including elements 60, 62, 63, 71 may be exactly the same as in the said previous patent. The connecting springs 100 in this application however replace the helical springs 73 and 73' and do their work. The improvement in this invention lies in the fact that the springs 100 are tensioned directly from the source of power and not by the roller 25 as are the helical springs 73, 73' in the previous invention.

If the follower 92 were moved slowly from one side to the other in time the cam 91 would strike the faces 93 or 94 on their corners, occasionally failing to function, and would wear badly. To prevent this I provide some form of snap action such that when the said follower passes its center line it will instantly snap squarely across the cam 91 and be operated thereby without mishap or excessive wear.

One of the many useful forms of snap action is shown by the double bevel 103 on the edge of the follower 92 over which the conically faced spring 104 travels.

The operation of the improved traverse mechanism will be clear from the foregoing, but may be briefly summarized as follows:

Assuming the parts to be in the positions illustrated in Fig. 2 and that the traverse is moving from left to right, when the projection on the carriage 40 engages the stop nut 61' the shipper rod 60 will be moved toward the right, from the full line to the broken line position shown in said figure. This moves the button 62 across its recess in the trigger 63 permitting the spring 64 to raise the trigger and engage the lower end of the bell crank arm 71 in the left hand groove therefor, thus locking the bell crank assembly against movement. As this occurs the left hand pin 102 will move the cam follower 92 toward the right and the spring 104 and bevel 103 will complete the follower's movement to the broken line position with a snap action, as above described. In this position the cam engaging surface 94 of the follower will be aligned with the cam 91, which is rotating constantly and the follower will be immediately lowered by the cam, its pivot 95 riding over the humps 96 and placing the lower spring 100 under tension, since the rock shaft 65 can not move by reason of the engagement between the arm 71 and trigger 63. The drive between the disc 21 and the wheel or roller 25 has not as yet been broken and the traverse toward the right therefore continues until the shipper rod 60 has moved its button 62 fully to the broken line position, thereby again depressing the trigger 63. This releases the bell crank arm 71 and permits the rock shaft 65 to move counterclockwise under the influence of the energy stored in the stressed spring 100, which movement is transmitted through the spring arms 66 and 61' to link 69 and bearing 27, thus lowering the shaft 26 and shifting the wheel 25 into engagement with the disc 20. This of course reverses the traverse, and the same cycle will be gone through when the carriage 40 engages the stop nut 61, except that the motion of the elements 60, 62, 92, 95, will be reversed, thereby stressing the upper spring 100 which in turn will move the parts 71, 65, 66, 69, 27, 26 and 25 in the reverse direction.

It is of course necessary that I use a definite physical structure to reveal my invention but many other structures can be used that would also embody my invention. Therefore I do not wish to limit myself to the exact physical structure nor mechanical details shown except as may be required by the appended claims.

What I claim is:

1. In traverse mechanism for a winding machine, said mechanism including a reversible drive comprising driving and driven elements, and means for moving at least one of said elements to reverse the drive, the combination of a cam; a follower operable by said cam; a spring connection between said follower and said element-moving means; and means independent of said driven element for actuating said cam to cause the follower to stress said spring connection as a preliminary to the movement of said element for reversing purposes.

2. In traverse mechanism for a winding machine, said mechanism including a traverse carriage, a reversible drive therefor comprising driving and driven elements, and means for moving at least one of said elements in opposite directions to reverse the drive, the combination of a cam; a follower mounted for movement between two positions in each of which it is operable by said cam in only one direction; a spring connec-

tion between said follower and said element-moving means; means for shifting said follower between its said two positions in timed relation to the traverse of the carriage; and means independent of said driven element for actuating said cam to cause said follower to stress said spring connection as a preliminary to movement of said element in either direction to reverse the drive.

3. In traverse mechanism for a winding machine, said mechanism including a traverse carriage, a reversible drive therefor comprising driving and driven elements, and means for moving at least one of said elements in opposite directions to reverse the drive, the combination of a cam; a follower mounted for both longitudinal and lateral movements, the lateral movements being between two positions in each of which the follower is operable by said cam in one longitudinal direction only; means for shifting said follower between its lateral positions in timed relation to the traverse of the carriage; a spring connection between said follower and the element-moving means; and means independent of said driven element for actuating said cam to cause it to move said follower longitudinally, whereby to stress the spring connection as a preliminary to movement of the drive element in either direction to reverse the drive.

4. In traverse mechanism for a winding machine, said mechanism including a traverse carriage, a reversible drive therefor comprising driving and driven elements, means for moving at least one of said elements in opposite directions to reverse the drive, and means for temporarily restraining said element-moving means, the combination of a cam; a follower mounted for both longitudinal and lateral movements, the lateral movements being between two positions in each of which the follower is operable by said cam in one longitudinal direction only; a spring connection between said follower and the element-moving means; means for shifting said follower between its lateral positions and for releasing the element-moving means from its restraint, in timed relation to the traverse of said carriage; and means independent of said driven element for actuating said cam to cause it to move said follower longitudinally during restraint of said element-moving means and thereby stress said spring connection, whereby the element-moving means will be moved to reverse the drive by the energy stored in said connection upon release of said restraint.

5. In traverse mechanism for a winding machine, said mechanism including a reversible drive comprising driving and driven elements, means for moving at least one of said elements to reverse the drive, and means for temporarily restraining said moving means, the combination of a cam; a follower mounted for longitudinal reciprocating and lateral swinging movements, said lateral movements being between two positions in each of which the follower is operable by said cam in one longitudinal direction only; a spring connection between said follower and said element-moving means; means for shifting said follower between its lateral positions prior to the conclusion of a traverse; and means for actuating said cam to cause the follower to stress said spring connection during the restraint of said moving means, whereby the latter may be moved to reverse the drive by the energy stored in said connection upon release of the restraint.

6. In traverse mechanism for a winding machine, said mechanism including a reversible

drive comprising driving and driven elements, means for moving at least one of said elements to reverse the drive, and means for temporarily restraining said moving means, the combination of a cam; a follower mounted for longitudinal reciprocating and lateral swinging movements, said lateral movements being between two positions in each of which the follower is operable by said cam in one longitudinal direction only; a spring connection between said follower and said element-moving means; means for shifting said follower between its lateral positions prior to the conclusion of a traverse; means for actuating said cam to cause the follower to stress said spring connection during the restraint of said moving means, whereby the latter may be moved to reverse the drive by the energy stored in said connection upon release of the restraint; and means for restraining reverse longitudinal movement of the follower while said connection is stressed.

7. In traverse mechanism for a winding machine, said mechanism including a reversible drive comprising driving and driven elements, means for moving at least one of said elements to reverse the drive, and means for temporarily restraining said moving means, the combination of a cam; a follower pivotally mounted for lateral swinging movements, said follower and pivot being also mounted for longitudinal reciprocation, said lateral swinging movements being between two positions in each of which the follower is operable by the cam in one longitudinal direction only; a spring connection between the follower and the element-moving means; means for shifting the follower between its lateral positions at approximately the conclusion of a traverse; means for actuating said cam to cause the follower to stress said spring connection during the restraint of the element-moving means, whereby the latter may be moved to reverse the drive by the energy stored in said connection upon release of the restraint; and a detent co-acting with the follower pivot for preventing reverse longitudinal movement of the follower while said connection is stressed.

8. In traverse mechanism for a winding machine, said mechanism including a reversible drive comprising driving and driven elements, and means for moving at least one of said elements to reverse the drive, the combination of a cam; a follower mounted for both longitudinal reciprocating and lateral swinging movements, said lateral movements being between two positions in each of which the follower is operable by said cam in one longitudinal direction only; a spring connection between said follower and said element-moving means; means for initiating the lateral movements of said follower at approximately the conclusion of a traverse; means for completing said lateral movements with a snap action; and means for actuating said cam to cause the follower to stress said spring connection as a preliminary to the movement of said element-moving means.

9. In traverse mechanism for a winding machine, said mechanism including a reversible drive comprising driving and driven elements, and means for moving at least one of said elements to reverse the drive, the combination of a rotatable cam; a follower for said cam mounted for both longitudinal and lateral movements, said follower having out-of-line cam engaging surfaces; a spring connection between said follower and said element-moving means; and means for moving said follower laterally to alternatively

aline its cam-engaging surfaces with the cam, whereby the latter may impart longitudinal movement to the follower to stress said spring connection as a preliminary to the movement of said element-moving means.

10. In traverse mechanism for a winding machine, said mechanism including a reversible drive comprising driving and driven elements, and means for moving at least one of said elements to reverse the drive, the combination of a rotatable cam; a follower for said cam mounted for longitudinal reciprocating and lateral swinging movements, said follower having an angularly disposed portion provided with an aperture for receiving said cam which aperture provides spaced cam-engaging surfaces only one of which may be alined with the cam at a time; a spring connection between said follower and said element-moving means; and means for moving said follower laterally to alternatively aline its cam-engaging surfaces with the cam, whereby the latter may impart longitudinal movement to the follower to stress said spring connection as a pre-

liminary to the movement of said element-moving means.

11. A cam follower for the traverse mechanism of a winding machine, comprising a body portion having means whereby it may be mounted for longitudinal reciprocating and lateral swinging movements, said body portion having an angularly disposed extension provided with a cam receiving aperture, which aperture provides spaced cam-engaging surfaces only one of which may be alined with the cam at a time.

12. A cam follower for the traverse mechanism of a winding machine, comprising a body portion having means whereby it may be mounted for longitudinal reciprocating and lateral swinging movements, said body portion having an angularly disposed extension provided with a cam receiving aperture, which aperture provides spaced cam-engaging surfaces only one of which may be alined with the cam at a time, said body portion also having a beveled surface for co-operation with a snap-action element.

PENROSE E. CHAPMAN.
